(57) **CLAIM**

The ornamental design for an ergonomic desk, as shown and described.

DESCRIPTION

FIG. 1 is a front perspective view of an ergonomic desk in the closed position showing my new design;

FIG. 2 is a front perspective view thereof in the open position with the writing surface in the lowered position;

FIG. 3 is a front view thereof;

FIG. 4 is a right elevation view thereof, the left side elevation view being a mirror image thereof;

FIG. 5 is a front perspective view thereof with the writing surface in the raised position;

FIG. 6 is a front view thereof; and,

FIG. 7 is a right elevation view thereof, the left side elevation view being a mirror image thereof.

1 Claim, 7 Drawing Sheets
